[57] **CLAIM**

The ornamental design for combined electrical plug and connector bodies, as shown and described.

DESCRIPTION

FIG. 1 is a top perspective view of the combined electrical plug and connector bodies according to our new design; FIG. 2 is a top plan view of the combined electrical plug and connector bodies of our new design shown in FIG. 1; FIG. 3 is a rear side elevational view of the combined electrical plug and connector bodies of our new design shown in FIGS. 1-2, which is substantially a mirror image of the front side;

FIG. 4 is a bottom plan view of the combined electrical plug and connector bodies of our new design shown in FIGS. 1-3;

FIG. 5 is a right end elevational view of the combined electrical plug and connector bodies of our new design shown in FIGS. 1-4; and,

FIG. 6 is a left end elevational view of the combined electrical plug and connector bodies of our new design shown in FIGS. 1-5.
